UNITED STATES PATENT OFFICE.

JAMES KAIN, OF NEW YORK, N. Y., ASSIGNOR OF TWO-THIRDS TO CHARLES HOWARD BOYER AND FRANK WOODRUFF BOYER, OF SAME PLACE.

PIPE-BOILER.

SPECIFICATION forming part of Letters Patent No. 656,121, dated August 14, 1900.

Application filed March 16, 1900. Serial No. 8,964. (No model.)

To all whom it may concern:

Be it known that I, JAMES KAIN, a citizen of the United States, residing at New York, (Brooklyn,) in the county of Kings and State 5 of New York, have invented new and useful Improvements in Pipe-Boilers, of which the following is a specification.

This invention relates to pipe-boilers, and has special relation to certain new and useful 10 improvements in the boiler forming the subject-matter of Letters Patent No. 532,071, granted to me January 8, 1895. In said patent I have shown, in connection with a horizontal steam-drum, two horizontal legs, a rear 15 transverse leg connecting the ends of said legs, and a series of pipes arranged at each side of the combustion-chamber, but alternately in opposite directions over the horizontal legs and communicating with the latter and with the steam-drum. In practice I 20 find that the provision of a continuous line of pipe at the side of the combustion-chamber tends to produce a sluggish circulation of water through said pipes, so that steam is liable 25 to form therein and the pipes become dry and burn out. Furthermore, should it become necessary to repair any one of these pipes the circulation through the entire line of pipe must be stopped, thus materially reducing 30 the capacity of the boiler to generate steam.

It is the main object of the present invention to overcome this objection and to provide a series of pipes inclosing the combustion-chamber at the sides and top, each of 35 said pipes having a circulation independent of the others, whereby any one of said pipes may be removed for repairs without in any manner interfering with the circulation of the water through the other pipes.

40 A further object of the invention relates to a novel arrangement of the pipes for securing exposure to the heat of the combustion-chamber of a large amount of heat-surface, whereby steam will be generated with great 45 rapidity and in large volumes.

To these ends the invention consists of the features of construction and the combination or arrangement of parts hereinafter described, and particularly pointed out in the claims.

50 I have illustrated my invention in the accompanying drawings, in which—

Figure 1 is a front perspective view. Fig. 2 is a rear elevation, and Fig. 3 is a transverse sectional view taken on the line 3 3 of Fig. 2.

55

The reference-numeral 1 in said drawings indicates the steam-drum, which is arranged at the upper front of the boiler and extends from side to side thereof. Communicating with said drum at or near its ends are two 60 vertical or nearly-vertical water-columns 2, which open into the lower side of the drum and extend thence downward to the front ends of two horizontal or nearly-horizontal water-legs 3, having about the same diameter as the water-columns. At their rear ends the water-legs 3 communicate with the ends of a third water-leg 4, which extends transversely from side to side of the rear end of the combustion-chamber. Communicating 65 with the transverse or back leg 4 are two alternating series of vertical or nearly-vertical pipes 5 6, which rise from the upper side of the leg to a point near the horizontal plane of the water-drum 1. At their upper ends 70 said pipes are coupled to a series of nearly-horizontal pipes 7 of somewhat less diameter, the latter series extending forward to the middle of the combustion-chamber or thereabout, where their ends are coupled to a double series of short vertical or nearly-vertical pipes 8 9, the former series being considerably the shorter. The series 8 are coupled 75 at their upper ends to the rearward ends of a series of horizontal or nearly-horizontal 80 manifolds 10, arranged substantially in the same horizontal plane and extending forward to the steam-drum 1, which they enter upon the rear side of said drum. The pipes 9 of the other series rise to a higher point, and 85 their ends are coupled to the rearward ends of a series of manifolds 12, which also extend forward to the steam-drum, entering the same about midway between the top and the rearward side of said drum. The two series of 90 manifolds are thus alternated in position, such arrangement being made necessary by the increased diameter of the manifolds relatively to the two series of pipes 8 9.

95 Each of the pipes 5 6 is entered upon its 100 front and from a point immediately below the coupling at the upper end by a closely-ar-

ranged series of pipes 13, of comparatively small diameter. These pipes are arranged in the same vertical plane in each group, and each series extends down to the middle point, 5 or thereabout, of the pipes 5 6. The members in each group or series are arranged at narrow intervals of separation in order to include as many pipes in each series as possible consistent with the proper circulation of 10 the products of combustion. The pipes of each series extend forward until beneath the manifold 10 or 12. They are then bent into a vertical position and enter the lower side of the manifolds. Each of the series of pipes 15 13 is known as a "flat." The arrangement of the drum, legs, pipes, and manifolds above briefly indicated is the same as in my patent above noted and need not be described more in detail.

20 As above stated, I dispense with the coil of pipes at each side of the combustion-chamber, which pipes formed a feature of my patented construction, and in lieu thereof employ the arrangement of pipes which will now 25 be described.

25 Tapped into the upper side of each of the side legs 3 is a series of upright pipes 14, each of which at its upper end is connected to a horizontal pipe 15. Each pipe 14 on one side 30 of the boiler is directly opposite a corresponding pipe 14 on the opposite side of the boiler, and the horizontal pipes 15 from corresponding pipes 14 have their inner ends secured in a three-way coupling 16. The pipes 14 extend 35 in vertical series from end to end of the legs 3 within the boiler-casing, and thereby inclose opposite sides of the combustion-chamber. The pipes 15 extend across the top of the combustion-chamber from side to side 40 thereof, while by the construction described a series of couplings 16 will be located centrally of the combustion-chamber—that is, they will have a relative position midway between the ends of the drum 1 and extend in 45 a straight line from the front to the rear of the combustion-chamber. A short pipe 17 connects each coupling 16 with a horizontal manifold 18, which extends in a line parallel with and above the line of couplings 16. The 50 manifold 18 at its forward end is curved upwardly and communicates with the drum 1 through the bottom thereof and about midway between the ends of said drum, as indicated at 19. At its rear end the manifold 18 55 is connected to the upper end of an upright pipe or uptake 20, which at its lower end communicates with the back leg 4. The manifold 18 is of such increased diameter or size relative to the pipes 15 as to enable it to accommodate the outflow from all of said pipes, 60 as will be understood. The upright or uptake pipe 20 is of the same size or diameter as the uptakes 5 6. In order to provide space for the manifold 18 and uptake 20, I remove 65 one or more of the flats 13, as clearly shown in Fig. 2.

In the present construction it will be seen

that in addition to the circulation through the flats 13 at the rear of the boiler I provide for a direct circulation from the side legs 3 7c through the pipes 14 and 15 and manifold 18 to the steam-drum and for a like circulation from the back leg 4 through the pipe 20. Furthermore, the circulation through each pipe-section 14 15 is independent of and distinct 75 from the circulation through the other pipe-sections, so that any one of said pipe-sections may be removed for repairs without in any manner interfering with the operation of the others. The pipes 15, manifold 18, and flats 80 13, being exposed to the direct heat from the combustion-chamber, will insure the rapid generation of steam, while the large number of pipes of comparatively-small diameter exposed to the heat will cause the steam to be 85 generated in large volumes or quantities. The uptake-pipes 5, 6, and 14, being located at the sides of the combustion-chamber, will not be subjected to such intense heat, and this fact, taken in connection with the fact 90 that the steam-drum 1 and water-columns 2 are located outside of the boiler-casing, while the legs 3 and 4 are inside the casing, but beneath the grate of the combustion-chamber, insures a rapid and positive circulation of 95 the water through all the pipes, as explained in my patent referred to. Further, by connecting the rear ends of the manifolds with the tops of the uptake-pipes I do away with "dead" ends and insure a complete circulation 100 of water throughout the boiler.

Having thus fully described my invention, what I claim as new is—

1. In a pipe-boiler, in combination with the steam-drum, water-columns and side water-legs, a horizontal manifold located centrally of and communicating with said drum, a series of vertical pipes communicating with each of said legs at intervals throughout its length, a series of three-way couplings, a series of horizontal pipes extending inward from the upper ends of said vertical pipes and into opposite sides of said couplings and a series of short vertical pipes connecting said couplings with said manifold, substantially 115 as described.

2. In a pipe-boiler, in combination with the steam - drum, water - columns and side and back water-legs, a horizontal manifold located centrally of and communicating at its forward 120 end with said drum, a vertical uptake connecting the rear end of said manifold with the back water-leg, a series of vertical pipes communicating with each of said side water-legs at intervals throughout its length, and 125 a series of horizontal pipes connecting the upper ends of said vertical pipes, said horizontal pipes communicating centrally at their length with said manifold, substantially as described.

3. In a pipe-boiler, in combination with the steam-drum,water-columns and side and back water-legs, a series of horizontal manifolds communicating at one end with the rear side 130

of said drum, a series of vertical uptakes communicating at their lower ends with the back water-legs and at their upper ends with the other, or rearward ends of said manifolds, 5 a series of flats arranged as described and connecting said manifolds and said uptakes, a horizontal manifold located centrally of and communicating at its forward end with said drum through the bottom thereof, a vertical 10 uptake connecting the rear end of said manifold with the back water-leg, a series of vertical pipes communicating with each of said side water-legs at intervals throughout its length, and a series of horizontal pipes connecting the upper ends of said vertical pipes, 15 said horizontal pipes communicating centrally of their length with said manifold, substantially as described.

In testimony whereof I have hereunto set my hand in presence of two subscribing witnesses.

JAMES KAIN. [L. S.]
